Primary Examiner — Patricia A Palasik(74) *Attorney, Agent, or Firm* — Connie R. Masters(57) **CLAIM**

The ornamental design for a vacuum drill press, as shown and described.

DESCRIPTION

FIG. 1 is a perspective front view of a vacuum drill press, showing our new design;

FIG. 2 is a perspective top rear view thereof;

FIG. 3 is a bottom view thereof;

FIG. 4 is a right side view thereof;

FIG. 5 is a left side view thereof;

FIG. 6 is a rear view thereof;

FIG. 7 is a front view thereof; and,

FIG. 8 is a top view thereof.

The broken lines in the drawings depict portions of the vacuum drill press and form no part of the claimed design.
